(57) **CLAIM**

The ornamental design for an electrical connector as shown
and described.

DESCRIPTION

FIG. 1 is a first perspective view of an electrical connector
showing my new design;

FIG. 2 is a second perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The uneven-length broken lines define the bounds of the
claimed design and form no part thereof. The remaining
even-length broken lines illustrate portions of the electrical
connector that form no part of the claimed design.
